UNITED STATES PATENT OFFICE.

CHARLES F. UEBELACKER, OF KINGSTON, NEW YORK, ASSIGNOR TO THE PECKHAM MOTOR TRUCK AND WHEEL COMPANY, OF SAME PLACE.

MAXIMUM-TRACTION TRUCK.

SPECIFICATION forming part of Letters Patent No. 598,403, dated February 1, 1898

Application filed September 10, 1897. Serial No. 651,227. (No model.)

To all whom it may concern.

Be it known that I, CHARLES F. UEBELACKER, a citizen of the United States, and a resident of Kingston, Ulster county, State of New York, have invented certain new and useful Maximum-Traction Trucks, of which the following is a specification.

The present invention has reference to car-trucks more especially intended for electric-railway service.

The object of the invention is to devise a truck of the maximum-traction type which shall be strong and durable and particularly adapted for modern electric-railway service.

15 The truck, as shown, is provided with a pair of thirty-three-inch driving-wheels and a pair of twenty-inch pilot-wheels, the pilot-wheels being adapted to swing under the sills of closed cars or the steps of open cars. These 20 dimensions are not to be regarded as inva- riable, but are those which in practice will be found preferable.

The car-body is adapted to rest on a bolster elastically suspended from the truck-frame 25 and located between the axle of the driving-wheels and the center of the truck and as near as practicable to the driving-axle, the bolster being provided with a king-pin and swivel-plates, as usual.

30 The motor for propelling the truck is sleeved to the axle of the driving-wheels with its free end elastically supported on the end of the truck-frame near the driving-wheels. The 35 relative positions of the bolster and the motor on the truck insure the necessary traction on the driving-wheels, giving about seventy-five per cent. of the load on such wheels.

To adjust the weight of the car-body on the pilot-wheels when running through a curve, 40 I provide on the truck-frame outside the pilot-wheels a suitably-shaped track, while to the car-body in the center of its longitudinal axis there is fixed a roller resting on such track and a compressible spring between the roller 45 and car-body. In the present construction the distance between the swivel-point of the truck and the roller on the car-body beyond the axle of the pilot-wheels is at all times substantially constant. In an application for 50 patent filed on even date with the present application, Serial No. 651,228, and to which

cross-reference is hereby made, I show a construction whereby the distance between the swivel-point of the truck and the bearing of a roller or slide on the track varies to shift 55 the leverage to a point where it is most desired.

It is to be understood, of course, that in practice the car-body is mounted on a pair of the trucks properly equipped with brake mechanism adapted to apply the brake-shoes to the 60 wheels of both trucks at one time.

In the accompanying drawings, which illustrate the present invention and which form a part of this specification, Figure 1 is a plan 65 view of a truck embodying my improvements. Fig. 2 is a side elevation, partly in section; and Fig. 3 is a cross-section on the line 3 3 of Fig. 1.

The same numerals of reference refer to 70 the same parts in all the views.

Referring to the drawings, 4 4^a indicate the pedestals, which are connected together by the upper duplex beams 5 and the lower beams 6, (both sides of the truck-frame being in all 75 respects the same,) and 7 7^a are the journal-boxes. The pedestals 4 are provided in their top members with recesses to receive spiral springs 8, which seat on top of the journal-boxes 7 to spring-cushion the truck-frame at 80 that point, and on the tops of the journal-boxes 7^a are seated the spiral springs 8^a, which extend between the members of beam 5 and bear against the top members of the pedestals 7^a, thus spring-cushioning the truck-frame at 85 that point. The duplex beams 5 are riveted in channels formed in the sides of the top members of the pedestals 4^a and extend beyond the pedestals, such extensions being supported by the under truss-beams 9^a, riveted 90 to beams 5 and to the bottoms of pedestals 4^a. To the outside of pedestals 4 are riveted the duplex end beams 10, supported from below by the truss-beams 9, which are riveted to the bottoms of pedestals 4 and to said beams 10. 95 At the bottom of the pedestals 4^a are secured the removable repairing-pieces 11.

The duplex beams 5 and 10 are carried around at the ends of the truck and extend transversely of the truck, with their members 100 5^a and 10^a, respectively, in contact, and serve to strengthen the structure at those points,

and to each end of the truck there is riveted an angle-beam 12. By forming the duplex beams 5 of continuous pieces extending from pedestals 4 beyond the pedestals at the pilot-wheels, to which latter pedestals said beams are independently riveted, and continuing said beams transversely at the end of the truck without break there is afforded superior strength to the structure.

10 The side frames of the truck are connected together centrally by the transverse tie-beam 13 of a depth corresponding to the space between beams 5 and 6 and is riveted to said beams, thus serving to hold the side frames in proper alinement.

15 The driving-wheels are indicated at 14 and their axle at 14^a and the pilot-wheels at 15 and their axle at 15^a.

20 The bolster 16, which is elastically supported, is provided with the usual swivel connections to receive the car-body and is swung from links pivoted to transoms supported on the duplex beams 5. The transoms 17 are arranged near the pedestals 4, so as to bring the bolster 16, which is supported thereby, near the axle of the driving-wheels, thus placing a larger percentage of the load on the driving-wheels than on the pilot-wheels. The transoms are riveted to plates 18, which in 25 turn are riveted to the duplex beams 5. The bolster 16 is suspended between the transoms 17, which serve as a guide for it and prevent it from moving in a direction longitudinal with the car.

30 35 The means for elastically supporting bolster 16 and affording to it a limited swinging movement transverse of the truck comprise the spring-plank 18^b, having end brackets 18^a, to which are pivoted the lower ends of four links 19, the upper ends of said links being pivoted to the transoms 17, as shown. The links 19 have normally a slight outward inclination, as seen in Fig. 3, the effect of which is to raise that side of the car-body toward which the bolster 16 moves when the truck runs into a 40 curve, thereby giving the effect of an additional superelevation of the outside rail of the curve. The spring-plank is provided with pockets 20, in which seat the spiral springs 21, whose upper ends seat in pockets 22, secured to the bottom of the bolster 16. Between the spiral springs 21, one near each end of the spring-plank, there is arranged a half-elliptic spring 23, whose ends rest in sockets 23^a on the spring-plank, the said spring 23 being connected to the bottom of the bolster 16 by a suitable elliptic-spring socket 23^b.

45 50 55 The motor for propelling the truck is indicated at 24, and it is sleeved on the axle 14^a of the driving-wheels in any approved manner, with its opposite end supported by the bar 25, which rests on spiral springs 26, suitably arranged in brackets 27, which are riveted to the transverse duplex beams 10^a at 60 that end of the truck. The weight of the motor augments the traction on the driving-wheels.

65 At that end of the truck outside the pilot-

wheels there is secured to the angle-bar 12 the plane track 28, preferably in the form of a sector of a circle whose center is the swivel connection 16^a between the truck and the car-body, its central portion being on the longitudinal axis of the truck.

To the car-sill, which is indicated at 29, is fixed a bolt 30, screw-threaded below its point 75 of attachment to the car-sill and provided with a pocket 31 and a nut 32 on said screw-threaded portion, which nut may be screwed up or down to increase or decrease the tension of spiral spring 33, which at its bottom seats in 80 a pocket 34, resting on the housing 35, whose upper extension is surrounded by the spiral spring 33 and in whose lower extension is journaled the roller 36, which is adapted to travel on the track 28 as the truck swivels under the 85 car when running through a curve. By turning the nut 32 the tension on spring 33 may be increased or decreased as desired, so as to increase or decrease the pressure of the roller 36 on its track 28. By this means the desired 90 amount of weight is secured on the pilot-wheels and the traction on the driving-wheels regulated as required.

It will be evident that if the car-body is mounted on a pair of trucks constructed, as 95 described, with the pilot-wheels of the trucks turned outward—that is, at the ends of the car—on entering a curve the roller 36 will be carried from the center of the pilot-axle toward that pilot-wheel of each truck which is in contact with the outside rail of the curve. This action will so divide the weight transferred from the car-body to the pilot-wheels through the roller 36 that the particular pilot-wheel in contact with the outside rail of each truck 100 will receive more weight than when the car is running on a straight track.

It is well known that under normal conditions the flange of the leading outside wheel in a four-wheeled truck is the one which is 110 pressed hard against the rail, and it is consequently this wheel which has a tendency to leave the track. Now with a pair of trucks such as herein described arranged under a car with the pilot-wheels outward the leading 115 outside wheel of the rear truck will be one of the drivers, and hence has ample pressure upon it to prevent its leaving the rail. The leading outside wheel of the forward truck will be that pilot-wheel toward which the 120 roller 36 moves and which receives from such movement an additional proportion of the whole weight transferred to the pilot-axle by said roller 36. This additional weight prevents the pilot-wheel of the leading truck 125 from leaving the track. The advantage of this mode of increasing the weight on the pilot-wheel which is in danger of leaving the rail when rounding a curve is twofold. First, no weight is deducted from that carried by 130 the drivers, as it is by all other constructions. Secondly, as the track 28 is plane and the roller 36 cylindrical there is no resistance to the movement of the roller on the track ex-

cept that due to friction, whereas all cam-
plates or similar devices depend on increasing
the tension on the spring in the combination
and consequently oppose a resistance to
the swiveling of the truck greater than that
due to friction alone. Such increased resist-
ance increases the pressure of the leading out-
side flange against the rail and renders that
wheel more apt to leave the track.

Having thus described my invention, what
I claim as new, and desire to secure by Letters
Patent, is—

1. In a car-truck the combination of front
and rear wheels, pedestals, side beams con-
necting the pedestals on each side of the truck,
duplex end beams secured to opposite faces
of the pedestals and projecting therefrom sep-
arated by approximately the thickness of the
pedestal, said end beams being connected
20 across the truck by a duplex cross-beam the
members of which are integral with said end
beams and are in contact with each other
across the truck.

2. In a car-truck, the combination of driv-
ing-wheels and pilot-wheels, front and rear
pedestals, upper duplex side beams and lower
side beams connecting the pedestals together,
separated duplex end beams riveted to oppo-
site faces of the pedestals at the driving
30 wheels, and connected across the truck by
members integral with the end beams, said
members being in contact across the end of
the truck, under truss-beams under the end
beams, and motor-supporting appliances on
35 the end of the truck equipped with the driv-
ing-wheels and connected to the duplex beam
across the truck.

3. In a car-truck provided with a pair of
driving-wheels and with a pair of pilot-wheels
40 of less diameter than the driving-wheels, the
combination with the pedestals, of duplex
upper side beams and lower side beams con-
necting the pedestals together, duplex end
beams riveted to the pedestals at the driving-
45 wheels and connected together at their ends
transversely, under truss-beams at each end
of the truck, and motor-supporting applica-
tions arranged on that end of the truck
equipped with the driving-wheels.

4. In a car-truck provided with a pair of
driving-wheels and with a pair of pilot-wheels
of less diameter than the driving-wheels, the
combination with the pedestals, duplex upper
50 side beams riveted to the pedestals at the driv-
ing-wheels and extending beyond the pedes-
tals at the pilot-wheels, to which pedestals
they are suitably riveted, and extending
around at their ends transversely of the truck
55 with their duplex members in contact with
each other, and duplex end beams riveted to
the pedestals at the driving-wheels and con-
nected together transversely at their ends, of
lower side beams connecting the pedestals to-
60 gether at their bottoms, and under truss-
beams at each end of the truck.

5. In a car-truck provided with a pair of
driving-wheels and with a pair of pilot-wheels

of less diameter than the driving-wheels, the
combination with the pedestals, of duplex
upper side beams riveted to the pedestals at
the driving-wheels and extending beyond the
pedestals at the pilot-wheels, to which they
are suitably riveted, lower side beams con-
necting the pedestals together at their bot-
toms, duplex end beams riveted to the pedes-
70 tals at the driving-wheels, under truss-beams
at each end of the truck, transverse end beams
connecting the side frames together and a
centrally-arranged transverse tie-beam of a
depth corresponding to the space between the
75 upper and lower side beams and suitably riv-
eted to said beams.

6. In a car-truck provided with a pair of
driving-wheels and with a pair of pilot-wheels
of less diameter than the driving-wheels, the
combination with the side frames comprising
pedestals, upper and lower side beams con-
necting the pedestals together and under
truss-beams at the ends of the side frames, of
a pair of transoms supported on the upper
80 side frames between the center of the truck
and the axle of the driving-wheels, a bolster
elastically supported between said transoms
and appliances sustaining the support for the
bolster and permitting the latter to swing
85 transversely of the truck.

7. In a car-truck provided with a pair of
driving-wheels and with a pair of pilot-wheels
of less diameter than the driving-wheels, the
combination with the pedestals, upper side
90 beams riveted to the pedestals at the driving-
wheels and extending beyond the pedestals at
the pilot-wheels to which they are suitably
riveted, end beams riveted to the pedestals
at the driving-wheels, suitable transverse
95 beams connecting the side frames together,
lower side beams connecting the pedestals to-
gether at their bottoms and under truss-beams
at the ends of the truck, of a pair of transoms
supported on the upper side beams between
100 the center of the truck and the axle of the
driving-wheels, a bolster elastically supported
between said transoms and appliances sus-
taining the support for the bolster and per-
mitting the latter to swing transversely of the
105 truck.

8. In a car-truck provided with a pair of
driving-wheels and with a pair of pilot-wheels
of less diameter than the driving-wheels, the
combination with the pedestals, upper side
110 beams riveted to the pedestals, lower side
beams connecting the pedestals together at
their bottoms, suitable transverse beams con-
necting the side frames together and under
truss-beams at the ends of the truck-frame,
115 of a pair of transoms supported on the upper
side frames between the center of the truck
and the axle of the driving-wheels, a spring-
plank hinged to the transoms to permit it to
swing transversely of the truck and a bolster
120 supported on said spring-plank by a series of
springs and operating between said transoms.

9. In a car-truck provided with a pair of
driving-wheels and with a pair of pilot-wheels

of less diameter than the driving-wheels, the combination with the side frames comprising pedestals, upper and lower beams connecting the pedestals together, end beams riveted to the pedestals at the driving-wheels, transverse beams connecting the side frames together at their ends and under truss-beams at the ends of the side frames, of a bolster elastically supported on the side frames near the driving-wheels and an electric motor sleeved to the axle of the driving-wheels with its opposite side suitably supported on the transverse beam at the end of the truck carrying the driving-wheels.

15 10. In a car-truck provided with a pair of driving-wheels and with a pair of pilot-wheels of less diameter than the driving-wheels, the combination with the side frames connected together by transverse end beams, a bolster supported on the side frames near the driving-wheels, an electric motor sleeved to the axle of the driving-wheels with its opposite side supported on the transverse beam at the end of the truck carrying the driving-wheels, and means for adjusting the weight of the car-body on the pilot-wheels, the said means attached to the truck-frame outside the pilot-wheels and to the bottom of the car-body contiguous thereto.

30 11. In a car-truck provided with a pair of driving-wheels and with a pair of pilot-wheels of less diameter than the driving-wheels, the combination with the side frames connected together by transverse end beams, a bolster supported on the side frames near the driving-wheels, and an electric motor sleeved to the axle of the driving-wheels with its opposite side suitably supported on the transverse beam at the end of the truck carrying the driving-wheels, of a suitable track on the transverse end beam outside the pilot-wheels, a roller adapted to travel on said track and connected with the bottom of the car-body at its end and a spring arranged between the roller and car-body, for the purpose set forth.

12. In a car-truck provided with a pair of driving-wheels and with a pair of pilot-wheels of less diameter than the driving-wheels, the combination with the side frames connected together by transverse end beams, a bolster elastically supported on the side frames near the driving-wheels, and an electric motor sleeved to the axle of the driving-wheels with its opposite side elastically supported on the transverse beam at the end of the truck carrying the driving-wheels, of a suitable track on the transverse end beam outside the pilot-wheels, a roller connected to the bottom of the car-body at its end and a spring arranged between the roller and the car-body, for the purpose set forth.

13. In a car-truck provided with a pair of driving-wheels and with a pair of pilot-wheels of less diameter than the driving-wheels, the combination with the side frames connected together by transverse end beams, a bolster provided with swivel-plate connections for

the car-body and elastically supported on the side frames near the driving-wheels, and an electric motor sleeved to the axle of the driving-wheels with its opposite side supported on the transverse beam at the end of the truck carrying the driving-wheels, of a track in the form of a sector of a circle whose center is the swivel connection between the truck and car-body, the said track located on the transverse end beam outside the pilot-wheels, a roller connected with the bottom of the car-body and adapted to travel on said track and a spring arranged between the roller and the car-body, for the purpose set forth.

14. In a car-truck provided with a pair of driving-wheels and with a pair of pilot-wheels of less diameter than the driving-wheels, the combination with the side frames connected together by transverse end beams, a bolster supported on the side frames near the driving-wheels, an electric motor sleeved to the axle of the driving-wheels, brackets, as 27, riveted to the transverse end beams 10^a, spiral 90 springs supported by said brackets and a bar, as 25, supported on said spiral spring and sustaining or supporting the free end of the motor, of means for adjusting the weight of the car-body on the pilot-wheels, the said 95 means secured partly to the truck and partly to the car-body outside of the pilot-wheels, substantially as set forth.

15. In a car-truck, the combination with the side frames and transverse end beams connecting the side frames together, of a bolster supported by the side frames near the driving-wheels, an electric motor sleeved on the driving-axle with its opposite end supported by appliances secured to the transverse beam 105 at the end of the truck carrying the driving-wheels, a track located on the transverse beam at the end of the truck carrying the pilot-wheels, a bolt secured to the bottom of the car-body, screw-threaded near its point of attachment to the car-body and provided with a pocket, as 31, and a nut, as 32, a roller adapted to coöperate with aforesaid track and journaled in a housing through which said bolt is adapted to operate and a spiral spring surrounding said housing between collar 31 and a collar near the bottom of the housing, substantially as set forth.

16. In a car-truck provided with a pair of driving-wheels and with a pair of pilot-wheels 120 of less diameter than the driving-wheels, the combination with the side frames, of an electric motor sleeved to the axle of the driving-wheels with its opposite side suitably supported on the end of the truck-frame outside 125 of the driving-wheels, a pair of transoms supported on the side frames near the driving-wheels, a spring-plank suspended from said transoms on two pairs of links and equipped with a system of springs, and a 130 bolster supported on said springs, substantially as set forth.

17. In a car-truck provided with a pair of driving-wheels and with a pair of pilot-wheels

of less diameter than the driving-wheels, the combination with the side frames, of an electric motor sleeved to the axle of the driving-wheels with its opposite side suitably supported on the end of the truck-frame outside of the driving-wheels, a pair of transoms supported on the side frames near the driving-wheels, a spring-plank, pairs of links suspending said spring-plank from the transoms and having normally a slight outward inclination, a pair of spiral springs and an intermediate elliptic spring supported on said spring-plank, and a bolster operating between the said transoms and connected to and supported by said system of springs.

18. In a car-truck provided with a pair of driving-wheels and with a pair of pilot-wheels of less diameter than the driving-wheels, the

combination with the side frames and suitable transverse end beams, of an electric motor 20 sleeved to the axle of the driving-wheels with its opposite end supported on the transverse beam at the end of the truck carrying the driving-wheels and a plane track on the transverse beam outside the pilot-wheels, a roller 25 suitably connected to the bottom of the car-body and adapted to travel on said track and a spring arranged between the roller and the car-body, for the purpose set forth.

Signed at New York, in the county and State 30 of New York, this 4th day of August, 1897.

CHARLES F. UEBELACKER.
